MACHINE FOR OPERATING UPON SOLES

Edward F. Small, Newton, Mass., assignor to
 Compo Shoe Machinery Corporation, Boston,
 Mass., a corporation of Delaware

Application July 13, 1950, Serial No. 173,517

53 Claims. (Cl. 69—1)

1

This invention relates to machines for operating upon soles for shoes and more particularly to a machine for reducing the marginal edge of the attaching face of outsoles and for simultaneously roughening such marginal edge to provide a receptive surface for sole-attaching cement according to the method disclosed in my co-pending application Serial No. 163,280 filed May 20, 1950.

For many years it has been general practice to round or die out outsole blanks and then to reduce the marginal portion of the forepart of the soles, to shank cut, and to roughen the reduced marginal portions, all in separate operations. Heretofore, machines have been illustrated to show that these operations possibly could be performed progressively by a series of operating tools. However, such machines are intricate, costly, and require experts to maintain them in adjustment.

A general object of this invention is to provide a machine for progressively treating the marginal portion of the attaching face of an outsole to reduce or bevel such portion and to simultaneously roughen same.

Another object of this invention is to provide a machine having but a single cutting tool for progressively treating the marginal portion of the attaching face of an outsole to reduce or bevel such portion and to simultaneously roughen same.

A further object of this invention is to provide a sole reducing and roughing machine that is simple in construction, easy to operate, and which considerably reduces costs of preparing outsoles.

Other objects of the invention will in part be obvious and will in part appear hereinafter. The invention accordingly comprises the features of construction, combination of elements, and arrangement of parts, which will be exemplified in the construction hereinafter set forth and the scope of the invention will be indicated in the claims.

For a fuller understanding of the nature and objects of the invention reference should be had to the following detailed description taken in connection with the accompanying drawings, in which:

Fig. 1 is a plan view of a machine for treating outsoles and which embodies features of my invention;

Fig. 2 is a side elevation of the machine shown in Fig. 1;

Fig. 3 is a partial side elevational view, on

2

an enlarged scale, and partly in section to better illustrate portions of the machine;

Fig. 4 is a fragmentary side elevation, similar to Fig. 3, showing the cutting blade drum in a lowered position to facilitate replacement of the cutting blade;

Fig. 5 is a fragmentary sectional view taken substantially along lines 3—3 of Fig. 3;

Fig. 6 is a front elevation showing on an enlarged scale detail of the feed screw;

Fig. 7 is a sectional view taken substantially along lines 1—1 of Fig. 8;

Fig. 8 is a partial plan view on an enlarged scale showing the relation of the cutting blade, edge guides, feed screw, and hold-down plate;

Fig. 9 is a partial plan view of the work table and showing the progress of a sole being operated upon;

Fig. 10 is a plan view of an outsole after being treated by the machine of my invention;

Fig. 11 is a transverse sectional view taken through the forepart portion of the sole shown in Fig. 10; and

Fig. 12 is a transverse sectional view taken through the shank portion of the sole shown in Fig. 10.

Referring to the drawings, there is shown a machine for treating the marginal portions of outsoles, which comprises a cast or fabricated frame 10 having an angle bar 11 secured to its inner front face and a like angle bar 12 secured to its inner rear face which serve to support the channel beams 13 and 14 upon which the entire sole cutting mechanism is mounted. The bracket 15 is bolted to the channel beams and its upper end is provided with a boss 16 having a bore in which the drive shaft 17 is journaled. The drum 18 is secured to the drive shaft which is adapted to be rotated by the sheave 19 connected by the belt 20 to the sheave 21 on the shaft of an electric motor 22 adjustably held to the beam 13.

The boss 16 on the bracket 15 is provided with an extended portion 23 of reduced diameter on which the arm casting 24 pivots. The end 25 of this arm casting is formed to receive the slide 26 which is held in place by the gib plates 27. The stud 28, upon which the idler drum 29 is mounted, is pivoted at 30 to the ears 31 extending from the slide and is adapted to be locked in a position where the drums 18 and 29 are in alignment to properly track the endless flexible cutting blade 32 shown in the form of a skip tooth bandsaw.

Preferably, as hereinafter explained, the drum

18 is driven in a counter-clockwise direction as viewed in Fig. 3. Also, since the drums 18 and 29 are spaced from each other the cutting blade 32 will have a portion between the drums which will form a straight line which will hereinafter be referred to as the path of the blade.

As shown in Figs. 3 and 4, the arm 24 is adapted to be moved about its pivot on the bracket 15 by a toggle mechanism to lower the drum 29 to facilitate replacement of the cutting blade. This may be accomplished by moving the hand lever 33 which is secured to the shaft 34 journalled in a bracket 35 secured to the beam 14. The arm 36, also secured to the shaft 34, is pivoted at 37 to the lower end of the lever 38 which is pivoted at 39 to the end 25 of the arm 24. The upper end of the lever 38 is bifurcated to fit over a stud 40 projecting from a rod 41 guided in a bore 42 in the arm 24 and in a bore 43 formed in an ear extending from the slide 26. The nuts 44 threaded to the rod 41 act to move the slide 26 rearwardly as the arm 24 is lowered so as to relieve the tension of the cutting blade. After replacement of a cutting blade, the hand lever is moved rearwardly until the stop screw 45 strikes against the base of the bracket 35 and the spring 46 is compressed by the collar 47 on the rod 41 and serves to move the slide 26 to again tension the cutting blade.

To guide the cutting blade 32 the usual form of roller edge guide 48 and adjustable guides 49 and 50 are provided and are held to a bracket 51 adjustably secured to the arm 24.

The work table 52 fits within an opening 53 formed in the top of the frame 10 and is provided with lugs 54 on its underside which straddle the forked member 55 to which the table is pivotably mounted by the pin 56. The member 55 is secured to a slide block 57 which is held by the gib plates 58 in a slot 59 formed in the bracket 60.

The height of the table 52 may be adjusted by turning the stud 61 one end of which is right hand screw threaded into a boss formed on the slide block 57 and the other end left hand screw threaded into the lug 62 formed on the bracket 60.

The sole support 63, shown in detail in Fig. 7, is provided with spaced holes 64 which slide over the studs 65 screw threaded to the table 52 and locked in position by the nuts 66. The springs 67 serve to bias the sole support upwardly away from the cutting blade 32 and the knurled nuts 68 may be used to adjust the height of the sole support to vary the distance between its sole contacting face 69 and the cutting blade.

The sole edge guide rolls 70 and 71 are held to the sole support by the shoulder screws 72 and, as best shown in Fig. 8, the roll 70 is located on the cutting edge side of the blade 32 while the roll 71 is located on the other side of the blade and spaced forwardly of the roll 70. This spacing of the guide rolls defines a line of feed which is oblique to the path of the cutting blade.

Feeding of a sole past the cutting blade is accomplished by the feed screw 75 which is secured by the set screw 76 to a shaft 77 journalled in the bracket 78 which is pivoted at 79 to the table 52. The bracket is biased upwardly by the spring 80 which is compressed by the screw 81 threaded into a bar 82 attached to the underside of the table 52. To

5 and the sole support face 69 the screw 83 threaded into the bracket 78 is provided with a head portion which contacts the underside of the table and acts as a stop to limit movement of the feed screw towards the sole support.

6 The feed screw shaft 77 is adapted to be constantly rotated in a clockwise direction, as viewed in Figs. 2, 3, and 4, by the belt 84 driven by an electric motor 85 indicated in Fig. 2.

7 The thread on the feed screw is left hand and of a shape which allows it to penetrate the flesh side of a sole presented thereto and as the screw is driven in a clockwise direction it tends to force the edge of the sole into contact with the guide rolls 70 and 71 as it feeds it past the cutting blade.

8 Also, as shown in Fig. 6, the feed screw is tapered so that its end farthest away from the cutting blade is of smaller diameter so as to 20 provide a bite between it and the sole support face 69 to allow easy entrance of a sole.

9 The table 52 and the sole support 63 are maintained at an angle with respect to the path of the cutting blade and preferably this angle corresponds to the desired angle to be cut on the shank portion of the soles being treated. To vary the angle, for cutting or reducing the forepart of the soles, a treadle 86 pivoted at 87 to the frame 10 is connected by the rod 88 to the table 52 in the manner shown in Fig. 2. The spring 89 located between the beam 13 and the collar 90 secured to the rod 88 serves to bias the table upwardly and the arm 91 which is locked to the rod by nuts 92 engages with the adjustable knurled stop nuts 93 when the treadle is in the depressed position as shown in Fig. 2 and against the stop nuts 94 when the table 52 is in its upper position.

10 To remove the leather dust created during 40 operation of the machine the duct 95 indicated in Fig. 2 may be connected to the usual factory blower system.

11 In operation of the machine described a sole S is placed flesh side down upon the table 52 and its heel end is inserted under the sole support 63 into the bite between the sole contacting surface 69 and the feed screw 75 substantially as shown in the position marked "Start" in Fig. 9. The feed screw thread then engages with the sole surface and urges the sole inwardly towards the guide rolls 70 and 71 as it positively advances the marginal edge of the sole past the cutting blade 32 which removes material from the sole in the form of a bevelled rand or skiving. When the ball line of the sole is reached the operator depresses the treadle 86 and consequently changes the angle of the sole contacting surface 69 with respect to the path of the cutting blade 32 so that less material is removed 60 from the sole.

12 The treadle is held depressed while the entire forepart of the sole is treated and is released when the ball line at the opposite side of the sole is reached to again allow the proper depth or angle of cut at the shank portion.

13 Feeding of the sole past the cutting blade and turning of the sole to effect a continuous cut from the heel end at one side of the sole to the heel end at the other side of the sole, or entirely around the sole, is automatic and of course the operator guides the sole out of the machine when it reaches the position marked "Finish" in Fig. 9.

14 By use of the toothed cutting blade 32 the leather fibres are somewhat pulled and combed

tip by the combined cutting and tearing action of the teeth. This leaves the cut surface roughened making an ideal surface for reception of sole attaching cement. As the cutting blade travels in a direction leading from the outer edge of the sole towards the center of the sole or away from the edge guides, no leather fibres are combed over the edge of the sole and thus a clean sharply defined sole edge is provided. Of course if roughening of the reduced margin is not desired a non-toothed band knife may be used.

Fig. 10 shows the attaching face of an out-sole treated by the machine above described and Figs. 11 and 12 illustrating sections through the forepart and shank portions respectively show the variance in the angle of cut obtained by varying the angle of the sole supporting surface 69.

It should be noted that no objectionable feed screw marks are left in the treated marginal edge of the sole since they are in the material removed by the cutting blade.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a machine for operating upon soles, a flexible endless cutting blade, spaced drums on which said blade is arranged to run, means for driving one of said drums to operate said blade, a sole support, said sole support being held at an angle with respect to the path of said blade, a sole edge guide, and means for holding a sole in contact with said support, for urging it into contact with said edge guide, and for progressively feeding its marginal edge past said blade.

2. In a machine for operating upon soles, a flexible endless cutting blade, spaced drums on which said blade is arranged to run, means for driving one of said drums to operate said blade, a sole support, said sole support being held at an angle with respect to the path of said blade, means for holding a sole in contact with said sole support and for feeding its marginal edge past said blade, and means for varying the angle of said sole support.

3. In a machine for operating upon soles, a flexible endless cutting blade, spaced drums on which said blade is arranged to run, means for driving one of said drums to operate said blade, a sole support, said sole support being held at an angle with respect to the path of said blade, means co-operating to hold a sole in contact with said support, to guide its edge, and to progressively feed its marginal edge past said blade, and means for varying the angle of said sole support.

4. In a machine for operating upon soles, a flexible endless cutting blade, spaced drums on which said blade is arranged to run, means for driving one of said drums to operate said blade, a sole support, said sole support being held at an angle with respect to the path of said blade, a

sole edge guide, means for holding a sole in contact with said support, for urging it into contact with said edge guide, and for progressively feeding its marginal edge past said blade, and means for varying the angle of said sole support.

5. In a machine for operating upon soles, a flexible endless cutting blade, spaced drums on which said blade is arranged to run, means for driving one of said drums to operate said blade, a sole support, said sole support being held at an angle with respect to the path of said blade, a sole edge guide secured to said support, and means for holding a sole in contact with said support, for urging it into contact with said edge guide, and for progressively feeding its marginal edge past said blade.

6. In a machine for operating upon soles, a flexible endless cutting blade, spaced drums on which said blade is arranged to run, means for driving one of said drums to operate said blade, a sole support, said sole support being held at an angle with respect to the path of said blade, a sole edge guide secured to said support, means for holding a sole in contact with said support, for urging it into contact with said edge guide, and for progressively feeding its marginal edge past said blade.

7. In a machine for operating upon soles, a flexible endless cutting blade, spaced drums on which said blade is arranged to run, means for driving one of said drums to operate said blade, a sole support, said sole support being held at an angle with respect to the path of said blade, sole edge guides secured to said support, said sole edge guides being spaced apart to define a line of feed, and means for holding a sole in contact with said support, for urging it into contact with said edge guide, and for progressively feeding its marginal edge past said blade.

8. In a machine for operating upon soles, a flexible endless cutting blade, spaced drums on which said blade is arranged to run, means for driving one of said drums to operate said blade, a sole support, said sole support being held at an angle with respect to the path of said blade, sole edge guides secured to said support, said sole edge guides being spaced apart to define a line of feed, means for holding a sole in contact with said support, for urging it into contact with said edge guide, and for progressively feeding its marginal edge past said blade, and means for varying the angle of said sole support.

9. In a machine for operating upon soles, a flexible endless cutting blade, spaced drums on which said blade is arranged to run, means for driving one of said drums to operate said blade, a sole support, said sole support being positioned above said cutting blade and held at an angle with respect to the path of said blade, a first sole edge guide secured to said support adjacent to the cutting edge of said blade, a second sole edge guide secured to said support adjacent the back edge of said blade and spaced forwardly of said first sole edge guide, said sole edge guides defining a line of feed oblique to the path of said blade, and means for holding a sole in contact with said sole support, for urging it into contact with said edge guides, and for progressively feeding its marginal edge past said blade.

10. In a machine for operating upon soles, a flexible endless cutting blade, spaced drums on which said blade is arranged to run, means for driving one of said drums to operate said blade, a sole support, said sole support being positioned

above said blade and held at an angle with respect to the path of said blade, a first sole edge guide secured to said support adjacent to the cutting edge of said blade, a second sole edge guide secured to said support adjacent the back edge of said blade and spaced forwardly of said first sole edge guide, said sole edge guides defining a line of feed oblique to the path of said blade, means for holding a sole in contact with said sole support, for urging it into contact with said edge guides, and for progressively feeding its marginal edge past said blade, and means for varying the angle of said sole support.

11. In a machine for operating upon soles, a flexible endless cutting blade, spaced drums on which said blade is arranged to run, a sole support, said sole support being held at an angle with respect to the path of said blade, a sole edge guide, means for driving one of said drums to operate said blade in a direction leading away from said sole edge guide, and means for holding a sole in contact with said sole support, for urging it into contact with said edge guide, and for progressively feeding its marginal edge past said blade.

12. In a machine for operating upon soles, a flexible endless cutting blade, spaced drums on which said blade is arranged to run, a sole support, said sole support being held at an angle with respect to the path of said blade, a sole edge guide, means for driving one of said drums to operate said blade in a direction leading away from said sole edge guide, means for holding a sole in contact with said sole support, for urging it into contact with said edge guide, and for progressively feeding its marginal edge past said blade, and means for varying the angle of said sole support.

13. In a machine for operating upon soles, a flexible endless cutting blade, spaced drums on which said blade is arranged to run, a sole support, said sole support being held at an angle with respect to the path of said blade, sole edge guides secured to said support, said sole edge guides being spaced apart to define a line of feed, means for driving one of said drums to operate said blade in a direction leading away from said sole edge guides, and means for holding a sole in contact with said support, for urging it into contact with said edge guides, and for progressively feeding its marginal edge past said blade.

14. In a machine for operating upon soles, a flexible endless cutting blade, spaced drums on which said blade is arranged to run, a sole support, said sole support being held at an angle with respect to the path of said blade, sole edge guides secured to said support, said sole edge guides being spaced apart to define a line of feed, means for driving one of said drums to operate said blade in a direction leading away from said sole edge guides, means for holding a sole in contact with said support, for urging it into contact with said edge guides, and for progressively feeding its marginal edge past said blade, and means for varying the angle of said sole support.

15. In a machine for operating upon soles, a flexible endless cutting blade, spaced drums on which said blade is arranged to run, a sole support, said sole support being positioned above said blade and held at an angle with respect to the path of said blade, a first sole edge guide secured to said support adjacent to the cutting edge of said blade, a second sole edge guide secured to said support adjacent the back edge of said blade and spaced forwardly of said first sole edge guide,

said sole edge guides defining a line of feed oblique to the path of said blade, means for driving one of said drums to operate said blade in a direction leading away from said sole edge guides, and means for holding a sole in contact with said sole support, for urging it into contact with said edge guides, and for progressively feeding its marginal edge past said blade.

16. In a machine for operating upon soles, a flexible endless cutting blade, spaced drums on which said blade is arranged to run, a sole support, said sole support being positioned above said blade and held at an angle with respect to the path of said blade, a first sole edge guide secured to said support adjacent to the cutting edge of said blade, a second sole edge guide secured to said support adjacent the back edge of said blade and spaced forwardly of said first sole edge guide, said sole edge guides defining a line of feed oblique to the path of said blade, means for driving one of said drums to operate said blade in a direction leading away from said sole edge guides, means for holding a sole in contact with said sole support, for urging it into contact with said edge guides, and for progressively feeding its marginal edge past said blade, and means for varying the angle of said sole support.

17. In a machine for operating upon soles, a flexible endless cutting blade, spaced drums on which said blade is arranged to run, means for driving one of said drums to operate said blade, a sole support, said sole support being located above said blade at a station between said drums and held at an angle with respect to the path of said blade, a rotatable feed screw located below said sole support adjacent the cutting edge of said blade, the axis of said feed screw lying substantially at a right angle to the path of said blade, and means for rotating said feed screw.

18. In a machine for operating upon soles, a flexible endless cutting blade, spaced drums on which said blade is arranged to run, means for driving one of said drums to operate said blade, a sole support, said sole support being located above said blade at a station between said pulleys and held at an angle with respect to the path of said blade, a rotatable feed screw located below said sole support adjacent the cutting edge of said blade, the axis of said feed screw lying substantially at a right angle to the path of said blade, means for rotating said feed screw, and means for varying the angle of said sole support.

19. In a machine for operating upon soles, a flexible endless cutting blade, spaced drums on which said blade is arranged to run, means for driving one of said drums to operate said blade, a sole support, said sole support being located above said blade at a station between said drums and held at an angle with respect to the path of said blade, a rotatable feed screw, means mounting said feed screw below said sole support and adjacent the cutting edge of said blade on an axis lying substantially at a right angle to the cutting edge of said blade for movement towards and away from said sole support, means urging said feed screw toward said sole support, and means for rotating said feed screw.

20. In a machine for operating upon soles, a flexible endless cutting blade, spaced drums on which said blade is arranged to run, means for driving one of said drums to operate said blade, a sole support, said sole support being located above said blade at a station between said pulleys and held at an angle with respect to the path of said blade, a rotatable feed screw, means

between it and said sole support into contact with said edge guides and to advance the marginal edge of the sole past said blade.

36. In a machine for operating upon soles, a flexible endless cutting blade, spaced drums on which said blade is arranged to run, a sole support, said sole support being located above said blade at a station between said drums and held at an angle with respect to the path of said blade, a first sole edge guide located below said sole support adjacent the cutting edge of said blade, a second sole edge guide located below said sole support adjacent the back edge of said blade, means for driving one of said drums to operate said blade in a direction leading away from said edge guides, a rotatable feed screw located below said sole support adjacent the cutting edge of said blade, the axis of said feed screw lying substantially at a right angle to the path of said blade, means for rotating said feed screw in a direction to urge a sole placed between it and said sole support into contact with said edge guides and to advance the marginal edge of the sole past said blade, and means for varying the angle of said sole support.

37. In a machine for operating upon soles, a flexible endless cutting blade, spaced drums on which said blade is arranged to run, a sole support, said sole support being located above said blade at a station between said drums and held at an angle with respect to the path of said blade, a first sole edge guide located below said sole support adjacent the cutting edge of said blade, a second sole edge guide located below said sole support adjacent the back edge of said blade, means for driving one of said drums to operate said blade in a direction leading away from said edge guides, a rotatable feed screw, means mounting said feed screw below said sole support and adjacent the cutting edge of said blade on an axis lying substantially at a right angle to said cutting edge for movement towards and away from said sole support, means urging said feed screw towards said sole support, and means for rotating said feed screw in a direction to urge a sole placed between it and said sole support into contact with said edge guides and to advance the marginal edge of the sole past said blade.

38. In a machine for operating upon soles, a flexible endless cutting blade, spaced drums on which said blade is arranged to run, a sole support, said sole support being located above said blade at a station between said drums and held at an angle with respect to the path of said blade, a first sole edge guide located below said sole support adjacent the cutting edge of said blade, a second sole edge guide located below said sole support adjacent the back edge of said blade, means for driving one of said drums to operate said blade in a direction leading away from said edge guides, a rotatable feed screw, means mounting said feed screw below said sole support and adjacent the cutting edge of said blade on an axis lying substantially at a right angle to said cutting edge for movement towards and away from said sole support, means urging said feed screw towards said sole support, means for rotating said feed screw in a direction to urge a sole placed between it and said sole support into contact with said edge guides and to advance the marginal edge of the sole past said blade, and means for varying the angle of said sole support.

39. In a machine for operating upon soles, a flexible endless cutting blade, spaced drums on which said blade is arranged to run, a sole sup-

port, said sole support being located above said blade at a station between said drums and held at an angle with respect to the path of said blade, a first sole edge guide located below said sole support adjacent the cutting edge of said blade, a second sole edge guide located below said sole support adjacent the back edge of said blade, means for driving one of said drums to operate said blade in a direction leading away from said edge guides, a rotatable feed screw, means mounting said feed screw below said sole support and adjacent the cutting edge of said blade on an axis lying substantially at a right angle to said cutting edge for movement towards and away from said sole support, means urging said feed screw towards said sole support, said feed screw being smaller in diameter at its end remote from said cutting edge, and means for rotating said feed screw in a direction to urge a sole placed between it and said sole support into contact with said edge guides and to advance the marginal edge of the sole past said blade.

40. In a machine for operating upon soles, a flexible endless cutting blade, spaced drums on which said blade is arranged to run, a sole support, said sole support being located above said blade at a station between said drums and held at an angle with respect to the path of said blade, a first sole edge guide located below said sole support adjacent the cutting edge of said blade, a second sole edge guide located below said sole support adjacent the back edge of said blade, means for driving one of said drums to operate said blade in a direction leading away from said edge guides, a rotatable feed screw, means mounting said feed screw below said sole support and adjacent the cutting edge of said blade on an axis lying substantially at a right angle to said cutting edge for movement towards and away from said sole support, means urging said feed screw towards said sole support, said feed screw being smaller in diameter at its end remote from said cutting edge, means for rotating said feed screw in a direction to urge a sole placed between it and said sole support into contact with said edge guides and to advance the marginal edge of the sole past said blade, and means for varying the angle of said sole support.

41. In a machine for operating upon soles, a flexible endless cutting blade, spaced drums on which said blade is arranged to run, means for driving one of said drums to operate said blade, a moveable sole support, said sole support being located above said blade at a station between said drums and pivoted for angular movement towards and away from said blade, means urging said sole support away from said blade, means for moving said sole support towards said blade, adjustable stops for limiting movement of said sole support, a first sole edge guide located below said sole support adjacent the cutting edge of said blade, a second sole edge guide located below said sole support adjacent the back edge of said blade, a rotatable feed screw located below said sole support adjacent the cutting edge of said blade, the axis of said feed screw lying substantially at a right angle to the path of said blade, and means for rotating said feed screw.

42. In a machine for operating upon soles, a flexible endless cutting blade, spaced drums on which said blade is arranged to run, means for driving one of said drums to operate said blade, a moveable sole support, said sole support being located above said blade at a station between said drums and pivoted for angular movement

towards and away from said blade, means urging said sole support away from said blade, means for moving said sole support towards said blade, adjustable stops for limiting movement of said sole support, a first sole edge guide located below said sole support adjacent the cutting edge of said blade, a second sole edge guide located below said sole support adjacent the back edge of said blade, a rotatable feed screw, means mounting said feed screw below said sole support and adjacent the cutting edge of said blade on an axis lying substantially at a right angle to said cutting edge for movement towards and away from said sole support, means urging said feed screw towards said sole support, and means for rotating said feed screw.

43. In a machine for operating upon soles, a flexible endless cutting blade, spaced drums on which said blade is arranged to run, means for driving one of said drums to operate said blade, a moveable sole support, said sole support being located above said blade at a station between said drums and pivoted for angular movement towards and away from said blade, means urging said sole support away from said blade, means for moving said sole support towards said blade, adjustable stops for limiting movement of said sole support, a first sole edge guide located below said sole support adjacent the cutting edge of said blade, a second sole edge guide located below said sole support adjacent the back edge of said blade, a rotatable feed screw, means mounting said feed screw below said sole support and adjacent the cutting edge of said blade on an axis lying substantially at a right angle to said cutting edge for movement towards and away from said sole support, means urging said feed screw towards said sole support, said feed screw being smaller in diameter at its end remote from said cutting edge, and means for rotating said feed screw.

44. In a machine for operating upon soles, a flexible endless cutting blade, spaced drums on which said blade is arranged to run, a moveable sole support, said sole support being located above said blade at a station between said drums and pivoted for angular movement towards and away from said blade, means urging said sole support away from said blade, means for moving said sole support towards said blade, adjustable stops for limiting movement of said sole support, a first sole edge guide located below said sole support adjacent the cutting edge of said blade, a second sole edge guide located below said sole support adjacent the back edge of said blade, means for driving one of said drums to operate said blade in a direction leading away from said edge guides, a rotatable feed screw located below said sole support adjacent the cutting edge of said blade, the axis of said feed screw lying substantially at a right angle to the path of said blade, and means for rotating said feed screw.

45. In a machine for operating upon soles, a flexible endless cutting blade, spaced drums on which said blade is arranged to run, a moveable sole support, said sole support being located above said blade at a station between said drums and pivoted for angular movement towards and away from said blade, means urging said sole support away from said blade, means for moving said sole support towards said blade, adjustable stops for limiting movement of said sole support, a first sole edge guide located below said sole support adjacent the cutting edge of said blade, a second

sole edge guide located below said sole support adjacent the back edge of said blade, means for driving one of said drums to operate said blade in a direction leading away from said edge guides, a rotatable feed screw, means mounting said feed screw below said sole support and adjacent the cutting edge of said blade on an axis lying substantially at a right angle to said cutting edge for movement towards and away from said sole support, means urging said feed screw towards said sole support, and means for rotating said feed screw.

46. In a machine for operating upon soles, a flexible endless cutting blade, spaced drums on which said blade is arranged to run, a moveable sole support, said sole support being located above said blade at a station between said drums and pivoted for angular movement towards and away from said blade, means urging said sole support away from said blade, means for moving said sole support towards said blade, adjustable stops for limiting movement of said sole support, a first sole edge guide located below said sole support adjacent the cutting edge of said blade, a second sole edge guide located below said sole support adjacent the back edge of said blade, means for driving one of said drums to operate said blade in a direction leading away from said edge guides, a rotatable feed screw, means mounting said feed screw below said sole support and adjacent the cutting edge of said blade on an axis lying substantially at a right angle to said cutting edge for movement towards and away from said sole support, means urging said feed screw towards said sole support, said feed screw being smaller in diameter at its end remote from said cutting edge, and means for rotating said feed screw.

47. In a machine for operating upon soles, a flexible endless cutting blade, spaced drums on which said blade is arranged to run, a moveable sole support, said sole support being located above said blade at a station between said drums and pivoted for angular movement towards and away from said blade, means urging said sole support away from said blade, means for moving said sole support towards said blade, adjustable stops for limiting movement of said sole support, a first sole edge guide located below said sole support adjacent the cutting edge of said blade, a second sole edge guide located below said sole support adjacent the back edge of said blade, means for driving one of said drums to operate said blade in a direction leading away from said edge guides, a rotatable feed screw located below said sole support adjacent the cutting edge of said blade, the axis of said feed screw lying substantially at a right angle to the path of said blade, and means for rotating said feed screw in a direction to urge a sole placed between it and said sole support into contact with said edge guides and to advance the marginal edge of the sole past said blade.

48. In a machine for operating upon soles, a flexible endless cutting blade, spaced drums on which said blade is arranged to run, a moveable sole support, said sole support being located above said blade at a station between said drums and pivoted for angular movement towards and away from said blade, means urging said sole support away from said blade, means for moving said sole support towards said blade, adjustable stops for limiting movement of said sole support, a first sole edge guide located below said sole support adjacent the cutting edge of said

blade, a second sole edge guide located below said sole support adjacent the back edge of said blade, means for driving one of said drums to operate said blade in a direction leading away from said edge guides, a rotatable feed screw, means mounting said feed screw below said sole support and adjacent the cutting edge of said blade on an axis lying substantially at a right angle to said cutting edge for movement towards and away from said sole support, means urging said feed screw towards said sole support, and means for rotating said feed screw in a direction to urge a sole placed between it and said sole support into contact with said edge guides and to advance the marginal edge of the sole past said blade.

49. In a machine for operating upon soles, a flexible endless cutting blade, spaced drums on which said blade is arranged to run, a movable sole support, said sole support being located above said blade at a station between said drums and pivoted for angular movement towards and away from said blade, means urging said sole support away from said blade, means for moving said sole support towards said blade, adjustable stops for limiting movement of said sole support, a first sole edge guide located below said sole support adjacent the cutting edge of said blade, a second sole edge guide located below said sole support adjacent the back edge of said blade, means for driving one of said drums to operate said blade in a direction leading away from said edge guides, a rotatable feed screw, means mounting said feed screw below said sole support and adjacent the cutting edge of said blade on an axis lying substantially at a right angle to said cutting edge for movement towards and away from said sole support, means urging said feed screw towards said sole support, said feed screw being smaller in diameter at its end remote from said cutting edge, and means for rotating said feed screw in a direction to urge a sole placed between it and said sole support into contact with said edge guides and to advance the marginal edge of the sole past said blade.

50. In a machine for operating upon soles, a frame, a drum mounted upon said frame on a horizontal axis, a drum spaced from said first mentioned drum and mounted upon a horizontal axis, a flexible endless cutting blade arranged to run on said drums, means for alining said drums to track said blade in the center of said drums, a toggle, means including said toggle for moving of one of said drums to tension said blade, means for driving one of said drums to operate said blade, a moveable sole support, said sole support being located above said blade at a station between said drums and pivoted for angular movement towards and away from said blade, means urging said sole support away from said blade, a treadle, means including said treadle for moving said sole support towards said blade, adjustable stops for limiting movement of said sole support, a first sole edge guide secured to said sole support adjacent the cutting edge of said blade, a second sole edge guide secured to said sole support adjacent the back edge of said blade and located forwardly of said first sole edge guide, said sole edge guides defining a line of feed oblique to the path of said blade, a rotatable feed screw moveably mounted below said sole support adjacent the cutting edge of said blade on an axis substantially at a right angle to the path of said blade, means biasing said feed screw towards said sole support, a stop for limiting

movement of said feed screw towards said sole support, said feed screw being smaller in diameter at its sole entering end to provide a bite between it and said sole support, and means for rotating said feed screw in a direction to urge a sole entered between it and said sole support into contact with said edge guides and to feed its marginal edge past said cutting blade.

51. In a machine for operating upon soles, a frame, a drum mounted upon said frame on a horizontal axis, a drum spaced from said first mentioned drum and mounted upon a horizontal axis, a flexible endless cutting blade arranged to run on said drums, means for alining said drums to track said blade in the center of said drums, a toggle, means including said toggle for moving of one of said drums to tension said blade, a work table on top of said frame, an opening in said work table forming a work station through which said blade passes, a sole support, said sole support being mounted above said blade at said work station and forming an angle with respect to the path of said blade, a treadle, means including said treadle for varying the angle of said sole support with respect to the path of said blade, a first sole edge guide secured to said sole support adjacent the cutting edge of said blade, a second sole edge guide secured to said sole support adjacent the back edge of said blade and located forwardly of said first sole edge guide, said sole edge guides defining a line of feed oblique to the path of said blade, means for driving one of said drums to operate said blade in a direction leading away from said edge guides, a rotatable feed screw moveably mounted below said sole support adjacent the cutting edge of said blade on an axis substantially at a right angle to the path of said blade, means biasing said feed screw towards said sole support, a stop for limiting movement of said feed screw towards said sole support, said feed screw being smaller in diameter at its sole entering end to provide a bite between it and said sole support, and means for rotating said feed screw in a direction to urge a sole entered between it and said sole support into contact with said edge guides and to feed its marginal edge past said cutting blade.

52. In a machine for operating upon soles, a frame, a drum mounted upon said frame on a horizontal axis, a drum spaced from said first mentioned drum and mounted upon a horizontal axis, a flexible endless cutting blade arranged to run on said drums, means for alining said drums to track said blade in the center of said drums, a toggle, means including said toggle for moving of one of said drums to tension said blade, a work table on top of said frame, an opening in said work table forming a work station through which said blade passes, a moveable sole support, said sole support being located above said blade at said station and pivoted for angular movement towards and away from said blade, means urging said sole support away from said blade, a treadle, means including said treadle for moving said sole support towards said blade, adjustable stops for limiting movement of said sole support, a first sole edge guide secured to said sole support adjacent the cutting edge of said blade, a second sole edge guide secured to said sole support adjacent the back edge of said sole edge guide, said sole edge guides defining a line of feed oblique to the path of said blade, means for driving one of said drums to operate said blade in a direction leading away from said

edge guides, a rotatable feed screw moveably mounted below said sole support adjacent the cutting edge of said blade on an axis substantially at a right angle to the path of said blade, means biasing said feed screw towards said sole support, a stop for limiting movement of said feed screw towards said sole support, said feed screw being smaller in diameter at its sole entering end to provide a bite between it and said sole support, and means for rotating said feed screw in a direction to urge a sole entered between it and said sole support into contact with said edge guides and to feed its marginal edge past said cutting blade.

53. In a machine for operating upon soles, a frame, a drum mounted upon said frame on a horizontal axis, a drum spaced from said first mentioned drum and mounted upon a horizontal axis, a flexible endless cutting blade arranged to run on said drums, means for alining said drums to track said blade in the center of said drums, a toggle, means including said toggle for moving of one of said drums to tension said blade, means for driving one of said drums to operate said blade, a work table on top of said frame, an opening in said work table forming a work station through which said blade passes, a sole support, said sole support being mounted above said blade at said work station and forming an angle with respect to the path of said blade, a 30 treadle, means including said treadle for vary-

ing the angle of said sole support with respect to the path of said blade, a first sole edge guide secured to said sole support adjacent the cutting edge of said blade, a second sole edge guide secured to said sole support adjacent the back edge of said blade and located forwardly of said first sole edge guide, said sole edge guides defining a line of feed oblique to the path of said blade, a rotatable feed screw moveably mounted below said sole support adjacent the cutting edge of said blade on an axis substantially at a right angle to the path of said blade, means biasing said feed screw towards said sole support, a stop for limiting movement of said feed screw towards said sole support, said feed screw being smaller in diameter at its sole entering end to provide a bite between it and said sole support, and means for rotating said feed screw in a direction to urge a sole entered between it and said sole support into contact with said edge guides and to feed its marginal edge past said cutting blade.
